UNITED STATES PATENT OFFICE

140,671

DESIGN FOR AN UMBRELLA BAG

Otto Pascal, Brooklyn, N. Y.

Application December 15, 1944, Serial No. 116,916

Term of patent 7 years

(Cl. D58—2)

To all whom it may concern:

Be it known that I, Otto Pascal, a citizen of the United States, residing at Brooklyn, in the county of Kings and State of New York, have invented a new, original, and ornamental Design for an Umbrella Bag, of which the following is a specification, reference being had to the accompanying drawing, forming part thereof.

The figure is a perspective view of an umbrella bag, showing my new design.

I claim:

The ornamental design for an umbrella bag, as shown.

OTTO PASCAL.
